MAX ROTHSCHILD
Inventor

By his Attorney
Howard Day

UNITED STATES PATENT OFFICE.

MAX ROTHSCHILD, OF NEW YORK, N. Y.

CIGAR-BOX-LID HOLDER.

1,028,607.

Specification of Letters Patent. Patented June 4, 1912.

Application filed September 15, 1911. Serial No. 649,497.

To all whom it may concern:

Be it known that I, MAX ROTHSCHILD, a subject of the Emperor of Germany, and a resident of the borough of Manhattan, 5 county, city, and State of New York, have invented certain new and useful Improvements in Cigar-Box-Lid Holders, as set forth in the following specification.

This invention relates to means for prop- 10 ping the open hinged cover of boxes such as cigar boxes.

In displaying cigars in a case it is desirable to expose the ornamental inner face of the box cover. To do this in a satisfactory 15 manner, the cover should be propped up and held in an elevated position firmly relatively to the box proper. The dispenser may then reach into the show-case and, by grasping the uptilted box-cover, remove the 20 box by the cover as a handle and allow the purchaser to remove a cigar from the box proper.

An object of the invention is to provide for this manner of dispensing cigars by a 25 device which will permit the ready adjustment and strutting of the box cover into and in any inclination desired.

It is a further object of the invention to combine in a single article means for so 30 propping a box cover throughout a wide range of small or large adjustments with means for holding a label or price tag across the inner face of the opened cover.

A still further object of the invention is 35 to improve the details of construction in an article of the class described.

The above and further objects of the invention will be clear from the following 40 specification and claims which should be read in connection with the illustrative embodiment of the invention shown in the accompanying drawings, which form a part of this application, in which like characters designate corresponding parts and in 45 which,—

Figure 1 is a side elevation of the device in working position, the box being shown in dot and dash lines; Fig. 2 is a front elevation of the device; Fig. 3 is an end elevation 50 of the same; Fig. 4 is a rear elevation; Fig. 5 is a plan view; Fig. 6 is a face view of the blank from which the body of the device is formed; and Fig. 7 is a detail view of the spurred arm.

55 The entire device may be termed a strut for box covers and may be formed of any

suitable sheet metal such as nickel plated sheet steel.

A blank 1 is punched to have the configuration shown in Fig. 6. The side lips 2 60 and 3 are overturned to form offset flanges similarly numbered in Figs. 1, 2 and 3, so that the rectangular portion 4, edged by these flanges 2 and 3 forms a label or price tag holder.

The end extension 5 is bent back first with a portion 5' at right angles to the label holder 4 and then with the portion 5'' substantially parallel but slightly approaching the label holder 4, the extending fingers 6 70 and 7 being slightly outturned so as to take over the edge of the box cover 8. These gripping parts may be termed a clip for engaging the box cover. The downwardly extending lip 9 is bent in at right angles to 75 form the lug 10 adapted to take under the heel 21 of the box cover 8.

The hinge-lug 11 is bent out at right angles to the plane of the label holder, to which the spurred arm 12 may be pivoted as 80 by the rivet 13. This arm 12 is a single fold of sheet metal having the two overlying lugs 14 with the perforations 15 for the passage of the rivet 13. The slot 16 separates the spring lips 17 from the lugs 14 and in the 85 assembled device they frictionally grip the hinge-lug 11. The arm 12 terminates in a sharp inturned spur 18 adapted to dig into the rear or hinging wall 19 of the box 20.

Operation: To apply the device to a box 90 cover the label holder 4 is placed against the inside face of the box cover and is pressed inwardly so that the fingers 6 and 7 slide over the rear of the box cover the part 5'' springing out slightly so as to insure a good grip 95 on the box cover and to adapt the device to various thicknesses of box covers. The lug 10 takes under the heel 21 of the box cover 8 to prevent the device sliding upwardly along the edge of the box cover.

The box cover may be adjusted into practically any position back of the vertical. The adjustment is not limited to one or two or three positions. The person manipulating the device needs merely to lift the box 105 cover up to the desired angle and at the same time to press in the arm 12 so that the spur 18 engages the rear wall 19 of the box. Any relative downward movement of the cover 8 or of the box 20 is then prevented 110 by the arm 12 with its spur 18 digging into the wall of the box.

What is claimed and what is desired to be secured by United States Letters Patent is:—

1. In combination, a label-holder; a clip-
5 flange for clamping said label-holder to a hinged box-cover; a hinge-lug bent out at right angles from the rear of said label-holder; a depending spurred arm pivoted to said hinge-lug; and provisions for retard-
10 ing the pivotal movement of said spurred arm so that it may be set in any angular position to engage the rear wall of the box to hold the lid at the desired angle.
2. In combination, a label-holder; a clip-
15 flange for clamping said label-holder to a hinged box-cover; a hinge-lug bent out at

right angles from the rear of said label-holder; a depending spurred arm pivoted to said hinge-lug, said arm comprising a symmetrical fold of sheet metal and provisions for retarding the pivotal movement of said spurred arm so that it may be set in any angular position to engage the rear wall of the box to hold the lid at the desired angle. 20

In witness whereof, I have signed my name to this specification, in the presence of two subscribing witnesses.

MAX ROTHSCHILD. 25
